BURIAL CASKET

John D. Beinert, New York, N.Y., assignor to Boyertown Burial Casket Company, Boyertown, Pa., a corporation of Pennsylvania

Filed Jan. 31, 1962, Ser. No. 68,583

Term of patent 7 years

(Cl. D19—1)

The single view is a perspective view of my new design.

The opposite side and end (not shown) are identical to the side and end shown in the drawing.

I claim:

The ornamental design of a burial casket, as shown and described.
